The ornamental design for a portable adjustable quartz halogen spotlight, as shown and described.

DESCRIPTION

FIG. 1 is a front perspective view of the portable, adjustable quartz halogen spotlight;

FIG. 2 is a front view thereof;

FIG. 3 is a side view thereof, the opposite side being a mirror image but for the omission of the wing nut in the pivot of the reflector bracket;

FIG. 4 is a back view thereof, with the feet in an alternative position;

FIG. 5 is a plan view thereof; and,

FIG. 6 is a bottom view thereof.

FIG. 1

FIG. 2

FIG. 3

FIG. 4

FIG. 5

FIG. 6
